Primary Examiner — Ryan Harvey(74) *Attorney, Agent, or Firm* — Sand, Sebolt & Wernow Co., LPA(57) **CLAIM**

The ornamental design for an exercise device, as shown and described.

DESCRIPTION

FIG. 1 is a top plan view of an exercise device in accordance with my design shown in a relaxed position;

FIG. 2 is a bottom plan view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a cross-section taken along line 7-7 of FIG. 3;

FIG. 8 is a cross-section taken along line 8-8 of FIG. 3; and, FIG. 9 is a right side elevation view of the exercise device of FIG. 1 shown in a stretched position.

The broken lines illustrate portions of the exercise device which form no part of the claimed design.

The dot-dot-dash lines show the cross-sections of FIG. 3 and form no part of the claimed design.

The claimed design is shown with a symbolic break in its length. The appearance of any portion of the article between the break lines forms no part of the claimed design.
